CASTING REEL FOR SEA-FISHING

Kent Tufvesson, Karlshamn, Sweden, assignor to
ABU AB, Svängsta, Sweden

Filed Jan. 21, 1971, Ser. No. 108,666

Claims priority, application Sweden, July 21, 1970,
218/70

Term of patent 14 years

Int. Cl. D22—05

U.S. Cl. D22—25

Fig. 3

Fig. 4

FIG. 1 is a top plan view of a casting reel for sea-fishing embodying my new design;

FIG. 2 is a view in perspective viewed from the operating handle end of the reel shown in FIG. 1;

FIG. 3 is a view in perspective viewed from the opposite end of the reel shown in FIG. 1; and

FIG. 4 is a view in elevation of the opposite end of the reel.

I claim:

The ornamental design for a casting reel for sea-fishing, as shown.
